UNITED STATES PATENT OFFICE.

JOHN J. KARTHEISER, OF CHICAGO, ILLINOIS, ASSIGNOR, BY DIRECT AND MESNE ASSIGNMENTS, TO KARBUAB COMPANY, OF CHICAGO, ILLINOIS, A CORPORATION OF ILLINOIS.

CARBURETER.

1,297,573.

Specification of Letters Patent. Patented Mar. 18, 1919.

Application filed June 1, 1915. Serial No. 31,444.

To all whom it may concern:

Be it known that I, JOHN J. KARTHEISER, a citizen of the United States, and a resident of Chicago, in the county of Cook and State of Illinois, have invented a certain new and useful Improvement in Carbureters, of which the following is a specification.

This invention relates to carbureters.

The primary object of the invention is to provide a carbureter constructed and arranged for properly proportioning the quantities of air and hydrocarbon supplied to the carbureter to produce practically a uniform explosive mixture of high efficiency under all conditions of hydrocarbon feed, for which the carbureter is designed and adapted; and to provide effective means for thoroughly breaking up or vaporizing the hydrocarbon and for thoroughly mixing the hydrocarbon vapor and air.

A further object of the invention is to provide, in connection with the carbureter proper, what may be designated an auxiliary carbureter particularly designed and adapted for use in starting the engine and for "idling," that is for running the engine at slow speed when it is standing still, whereby the engine may be kept warm, even in cold weather and may be quickly and conveniently started regardless of weather conditions.

To effect the foregoing objects, a carbureter of my invention comprises the various features, combinations of features and details of construction hereinafter described and claimed.

In the accompanying drawing in which my invention is fully illustrated,

Figure 1 is a side view of my improved carbureter.

Fig. 2 is a sectional elevation thereof on the line 2-2 of Fig. 4.

Fig. 3 is a sectional elevation thereof on the line 3-3 of Fig. 4.

Fig. 4 is a sectional elevation thereof on the line 4-4 of Fig. 3.

Fig. 5 is a top plan view of my improved carbureter with the manifold connection removed.

Fig. 6 is a sectional plan view on the line 6-6 of Fig. 1.

Figs. 7 and 8 are sectional bottom-plan

views on the lines 7-7 and 8-8, respectively, of Fig. 3; and

Fig. 9 is a sectional plan view on the line 9-9 of Fig. 3.

My improved carbureter comprises a body portion, designated as a whole A, formed in which is a mixing chamber A'. To provide access to said chamber, one side thereof is closed by a removable plate *a* and, if considered desirable, my invention contemplates making both sides thereof thus removable.

The carbureter is provided with a discharge opening 1 which connects the mixing chamber A' directly with the manifold or manifolds.

My improved carbureter is of the multiple jet type, comprising a plurality of separate nozzles and corresponding air admission openings, so arranged and controlled that they may be brought successively into communication with the mixing chamber A'. As shown, there are five separate nozzles designated, respectively, 2, 3, 4, 5 and 6 located in separate air admission passageways 2', 3', 4' and 6'. Hydrocarbon is supplied to the nozzles from a float reservoir A² through passageways 7 formed in a fitting 8 which, as shown, is removably secured to the lower end of the body portion of the carbureter, said fitting being skeletoned to permit air to pass the same freely and enter the air admission passageways 2', 3', 4', 5' and 6'.

As compared with hydrocarbon supply nozzles heretofore used, the nozzles of my improved carbureter are characterized by the feature that the jet orifices thereof are relatively much smaller, which in combination with the separate air admission passageways therefor and the means for bringing the same separately and successively into communication with the mixing chamber A', obviously renders it possible to produce a practically uniform and properly proportioned explosive mixture for different feeds, thus insuring maximum efficiency and economy of hydrocarbon.

My invention contemplates the use of any desired or approved form of float reservoir A² and the same need not therefore, be described in detail.

In order to provide for varying the proportions of air and of hydrocarbon so as to

produce an explosive mixture which shall be richer or poorer in hydrocarbon as may be desired, means are provided for varying the effective suction exerted on the nozzles by the motor when said nozzles are in communication with the mixing chamber, which will operate to draw relatively more or less hydrocarbon from said nozzles as said suction is increased or decreased. In the preferable construction shown, said means consists of a valve which controls the central air admission passageway 2', but my invention contemplates the use of valves for thus controlling any desired number of said passageways. With this construction it is obvious that, if only the air passageway 2' is in communication with the mixing chamber A', partly closing the valve which controls said passageway, will reduce the size of said air admission passageway and will increase the suction on the nozzle 2, thus increasing the relative proportion of hydrocarbon and producing a rich mixture. On the other hand, opening said valve will reduce the suction on said jet nozzle and will increase the relative quantity of air, thus producing a "lean" mixture. In like manner, if two or more of said passageways are open to the mixing chamber A', closing the valve controlling said air admission passageway 2', will increase the suction on all of said nozzles, increasing the proportion of hydrocarbon, and by reducing the aggregate size of the air openings, correspondingly reducing the proportion of air, thus producing a richer or leaner mixture as said valve is closed or opened.

While my invention contemplates the use of any desired or approved form of valve for thus controlling said air admission passageway, I prefer the form of valve shown in the drawings, which consists of a plate 9 fitted to and movable endwise in guide grooves formed in the lower end of the body portion A of the carburetor, endwise movement of said valve in opposite directions operating to open and close said air admission passageway 2'. The inner end of said valve is slotted as shown at 10 to receive the jet nozzle 2.

The outer end of the valve 9 projects beyond the side of the body portion A of the carburetor and pivotally connected thereto is a lever 11, which is pivoted between its ends to a plate or bracket 12 which projects laterally from the side of the body portion of the carburetor. A spring 13 which connects the outer end of the lever 11 with a fixed part of the carburetor casing will operate to impart pivotal movement to the lever 11 in a direction to open the valve 9. The edge 16 of the lever 11, between this pivot and the end thereof which is connected to the valve 9 forms a cam surface which operates with the throttle lever to close the

valve 9 against the force of the spring 13, when the throttle lever is turned pivotally to close the throttle valves.

Pivotal movement of the lever 11 in the direction to open the valve 9 is limited by means of an adjustable stop, which, in the case of an automobile, is adapted to be operated by means of the driver of the car. As shown, said stop consists of a button 17 secured to a wire 18 which extends through a hole formed in a post 19 pivoted to the lever 11 so as to turn freely about its longitudinal axis, contact of said stop with said post operating to limit the pivotal movement of said lever under the influence of the spring 13, as shown, the button 17 is adjustably secured to said wire 18 by means of a set-screw whereby said button may be quickly and conveniently adjusted toward and from the post 19 to bring said button in proper relation to said post.

Endwise movement is adapted to be imparted to the wire 18 by means of a usual lever mounted on the steering post of the car, not shown, buckling of said wire being prevented by means of a tube 20 through which said wire passes and which extends to within a short distance of the stop 17.

The air admission passageways 2', 3', 4', 5' and 6' and thus the nozzles 2, 3, 4, 5 and 6 and the discharge opening 1 are controlled by suitable throttle valves, the valve which controls said air admission passageways and jet nozzles being constructed and arranged for opening and closing said air admission passageways separately and in succession. As shown said valves and the means for operating the same are as follows:—Extending across the mixing chamber A' and having bearings in the side walls of the body portion A of the carburetor are shafts 21 and 22, the outer ends of said shaft bearings being preferably closed to prevent leakage around same. Mounted on said shafts, respectively, are what may be appropriately designated shutter valves 23 and 24, and 25 and 26. Pivotal movement in opposite directions—that is, toward and from each other—is adapted to be imparted to the shutter valves 23 and 24, and 25 and 26 by means of operative connection with a stub shaft 27 mounted to rotate in suitable bearing formed in an off-set portion a' of the removable side wall a of the carburetor casing and a bearing plate a' secured between said removable side wall a and the side of the carburetor. Oscillatory movement is adapted to be imparted to said stub shaft 27 by means of a usual operating mechanism, comprising a crank arm or lever 28 secured to said shaft so as to rotate therewith, and a connecting rod 29 attached to said lever 28.

As shown, the shutter valves are operatively connected with the shaft 27 in the following manner:—Secured to the stub shaft 130

27 in the recess 30 formed by the off-set portion *a'* of the removable side wall *a* is a pinion 31 which intermeshes with pinions 32 and 33 secured to rotate with the shafts 21 and 22, respectively, whereby oscillation of said shaft 27 will impart rotation to the shafts 21 and 22 in the same direction. Secured to the shafts 21 and 22, respectively, within the mixing chamber A' are pinions 34 and 35, and 36 and 37. The pinion 34 on the shaft 21 intermeshes with the pinion 36 on the shaft 22 and the pinion 35 on the shaft 21 intermeshes with the pinion 37 on the shaft 22. The shutter valves 23 and 26 and the pinions 34 and 37 are secured to rotate with their respective shafts, as by pins 38, while the pinions 35 and 36 are mounted to turn freely on their shafts and are secured to rotate with the shutter valves 24 and 25, mounted on said shafts, respectively.

With the described construction it is obvious that oscillation of the stub shaft 27 will operate to impart pivotal movement to the valves of each pair of shutter valves 23 and 24, and 25 and 26, toward and from each other.

The air passageway 2' communicates with the mixing chamber at a point directly beneath the meeting edges of the shutter valves 25 and 26, when said valves are closed, whereby the initial movement of said shutter valves in opening will uncover said passageway 2' so that the suction of the motor will operate to draw a mixture of hydrocarbon vapor and of air into the mixing chamber from said air admission passageway and the nozzle 2 located therein. As shown, also, the passageways 3', 4', 5' and 6' communicate with the mixing chamber A' at points on opposite sides of said mixing chamber and about equal distances from the meeting edges of the shutter valves 25 and 26 when closed, said passageways being arranged two on each side of said mixing chamber. To provide for opening and closing said air admission passageways 2', 3', 4', 5' and 6' in succession, as said shutter valves open and close, openings 39 and 40 are formed in the edges of the shutter valves 25 and 26, respectively, in line with an air admission passageway controlled by said shutter valves, respectively. As shown, the opening 39 is in line with the air admission passageway 3' controlled by the valve 25 and the opening 40 with the passageway 4' controlled by the valve 26. Also formed on said shutter valves, in line with said openings 39 and 40, are projections 41 and 41', which are of substantially the same size as said openings, respectively, and are adapted to fit into said holes or openings when said shutter valves are closed. Said openings 39 and 40 and projections 41 and 41' are made of different operative lengths circumferentially of said shutter valves, so that at a desired interval

of time before or after full opening of the passageway 2', preferably immediately after full opening thereof, the inner end of the opening 39 will begin to pass over the air admission passageway 3', and, in like manner, the inner end of the opening 40 will pass over the passageway 4', and the outer ends of the projections 41 and 41' will pass over and uncover the passageways 5' and 6' respectively.

With the described construction, it is obvious that the quantity of hydrocarbon feed to the engine may be regulated with great precision and nicety and also that the proportion of air and hydrocarbon vapor may be accurately varied to produce an effective mixture.

With the described construction, it is also obvious that, when the lever 28 is turned to separate or open the valves 25 and 26 a sufficient distance to open or close the air admission passageway 2', the shutter valves 23 and 24 which control the discharge opening 1 will be opened a corresponding distance, and that the opening of said shutter valves will continue as the turning of the operating lever 28 continues, so as to open in succession the air passageways 3', 4', 5' and 6'. Due to the fact that the size of the discharge opening 1 from the carburetor is thus graduated to correspond to the opening or uncovering of different numbers of air admission passageways, it is obvious that the mixture in the chamber A' will pass through the discharge opening from the carburetor at a high velocity, which will cause the particles of hydrocarbon to strike the shutter valves 23 and 24, the impact operating to break up said particles of hydrocarbon. Also, as the air and hydrocarbon vapors pass out of the carburetor, they will converge toward the contracted discharge opening, thereby effecting an intimate association and intermixing thereof, which will produce a uniform explosive mixture of high efficiency.

Preferably, also, I supplement the breaking up and mixing action of the shutter valves 23 and 24 by baffle plates which extend across the mixing chamber A' between the air admission openings and the discharge opening and which are adapted to impart an eddying effect to the current of mixed air and hydrocarbon vapor passing through said mixing chamber, the impact of the hydrocarbon particles against said baffle plates operating to break up and finely subdivide the same and the eddying action produced thereby operating to effect a thorough mixing of the air and hydrocarbon vapor. As shown, said baffle comprises inclined and upward divergent plates 42 and 43 which extend across the mixing chamber A' between the shafts 21 and 22 and substantially at right angles thereto, the inclination of said

plates being such that they will divert the current passing from the air admission openings to the discharge opening, breaking it up into a number of conflicting currents, which will produce the eddying and mixing effect desired. My invention, however, contemplates the use of any desired or approved form of baffle arranged in any desired manner.

10 As previously stated, the throttle lever 28 cooperates with the cam surface 16 on the lever 11, which operates the valve 9 controlling the air admission passageway 2', to move said lever 11 pivotally against the force of the spring 13 applied thereto, so as to close said valve when said throttle lever is turned to close the throttle valves 23, 24, 25 and 26, the relation being such that turning said throttle lever to fully close the 15 throttle valves will also fully close the valve 9. The relation is such also that, when the throttle lever is turned to open the throttle valves, said throttle lever will release the lever 11 thus permitting said spring to turn 20 said lever 11 to open the valve 9. As previously stated however, the extent of opening of said valve 9 by the spring 13 may be regulated and controlled by means of the stop 17, so that, even when the throttle valves 25 are fully opened the opening of the valve 9 may be limited as desired, or wholly or partially closed against the force of the 30 spring 13.

While I consider the use of the valves 23 and 24 as preferable, as regards most of the features of my improved carbureter, said valves are not essential and may be omitted without departure from the invention.

The object of my invention, as it relates to 40 providing an auxiliary carbureter particularly designed and adapted for use in starting the engine and for "idling," the construction of my improved carbureter is as follows:—Formed in a wall of the carbureter 45 casing A and extending through the same from top to bottom is a hole or passageway 44, the lower end of which is preferably enlarged as shown at 45 and formed at the upper end of which is a valve chamber provided 50 with a valve seat 46 for a valve 47, said valve being controlled in the manner presently to be described. Extending upwardly into the enlarged lower end 45 of said passageway, is a jet nozzle 48 which is secured in the fitting 55 8 and which communicates with the float reservoir A² by means of a passageway which forms a continuation of the passageways 7 through which hydrocarbon is supplied to the jet nozzles of the main carbureter.

The valve 47 is provided with a valve stem 49 which is movable endwise in a bearing formed in a screw plug 50 which closes the outer end of the valve chamber 51 formed 65 at the upper end of the passageway 44, said

valve being maintained normally closed by means of a spring 52 inserted between the screw plug 50 and the upper side of the valve 47 and which surrounds the valve stem 49 as a guide.

70 Communicating with the valve chamber 51 is a pipe or tube 53 which extends across the discharge opening 1 from the mixing chamber A', above the shutter valves 23 and 24 and which is provided with holes or openings 54 through which said pipe communicates with said discharge opening. When the valve 47 is closed, communication between the passageway 44 and the pipe 53 will be cut off, so that the suction of the motor will have 80 no effect on the jet nozzle 48. When said valve 47 is open, as shown in Fig. 3 of the drawings, however, said pipe 53 will be in communication with the passageway 44 so that the suction of the motor will operate 85 in the usual manner to draw a supply of air and hydrocarbon vapor through the open lower end of the passageway 44 and from the jet nozzle 48, which will form an explosive mixture, the supply of which will 90 be sufficient for running the engine. When said valve 47 is only partly opened, a "lean" mixture will be formed which however, will be sufficient for running the engine when "idling." Also, when said valve is fully 95 opened, the explosive mixture will be rich in hydrocarbon thus providing a priming charge by means of which the motor may be quickly and conveniently started.

As shown, said valve 47 is adapted to be 100 operated in the following manner:—Secured in the end of the valve stem 49 which projects above the screw plug 50 and projecting laterally therefrom is a wire 55 which is adapted to ride on a cam surface 56 formed 105 on the upper edge of an upward tubular extension 57 of the screw plug 50, the relation being such that, as said valve is turned pivotally in one direction, the valve 47 will be raised to open the same against the force of 110 the spring 52 applied thereto and when turned in the opposite direction will permit said valve to be closed by said spring.

To prevent the valve stem 49 from cocking and binding in its bearings, which might 115 interfere with the designed operation, therefore, duplicate cam surfaces 56 are provided on opposite sides of said valve stem, and the rod or wire 55 projects at both sides of the valve stem so as to engage both of said cams. 120

As previously stated, the valve 47 will be maintained normally closed by means of the spring 52 applied thereto, with the wire 55 resting on the low points of the cams 56. In accordance with my invention, means are 125 provided for operating said valve, whereby when the throttle valves 23 and 24, and 25 and 26 are closed, said valve 47 will be opened. As shown, the means for thus opening said valve are as follows:—Pivoted to a 130

rigid part of the body portion A of the carburetor is a bell crank lever 58 one arm of which is connected to the rod 55 secured in the valve stem 49 by a link 59 and the opposite end of which projects into the path of movement of an upward extension 60 of the throttle lever 28, when the valve 47 is closed and the throttle valves are open, so that turning the throttle valve lever 28 to close 10 said throttle valves will operate to turn the valve stem 49 and thus, through said rod 55 and the cams 56, to raise and open the valve 47.

To provide for varying the angular movement of the valve stem 49 and thus the opening of the valve 47 by the throttle lever extension 60, means are provided for adjusting the point of attachment of the link 59 to the rod or wire 55. As shown, said link 59 is connected directly to a block 61 provided with a hole or opening through which the rod 55 extends and which is adapted to be secured in any desired adjusted position on said rod 55 by a set-screw 62. With the 25 described construction, it is obvious that the farther the point of attachment of said block 61 from the axis of the valve stem, the smaller will be the valve opening and vice versa. Also to provide for varying the 30 point of attachment of the link 59 to the rod 55 without varying the angular adjustment of the valve stem, means are provided for varying the length of said link. As shown, this is effected by making said link in sections connected by a turn-buckle indicated 35 at 63.

Pivotal movement is adapted to be imparted to the valve stem 49 to wholly or partially open said valve by means of a 40 wire 64 which passes freely through a hole formed in the block 61 and adjustably secured to which, as by means of a set-screw, is a button 65. Endwise movement is adapted to be imparted to the wire 64 by means 45 of a usual lever, which, in the case of an automobile, is mounted on the steering post of the car, not shown, so as to be conveniently accessible to the drive of the car, buckling of said wire being prevented by means 50 of a tube 66 through which said wire passes and which terminates a sufficient distance in front of the rod 55 to provide for desired pivotal movement of the valve stem 49 to open and close the valve 47.

55 In some types of engines, particularly eight cylinder engines, the cylinders comprise series connected to the carburetor by means of separate manifolds which, however, communicate with a common discharge 60 opening of the carburetor. This is objectionable for the reason that it is found in practice that the suction of the cylinders will operate not only to draw explosive mixture from the carburetor, but will also operate to draw or "steal" explosive mixture 65

from the branch of the manifold which supplies the other cylinders, whereby the initial suction of the cylinders will act on a highly rarefied mixture which may result in an insufficient supply of explosive mixture being 70 furnished to the cylinders to develop the full designed efficiency of the motor.

To overcome this objection, where the manifold connection, designated as a whole 67, comprises separate branches, I construct 75 said manifold connection with a depending plate 68 which is adapted to extend into the discharge opening 1 of the carburetor when said manifold connection is attached thereto and to divide the same into separate passageways or chambers, which respectively connect the mixing chamber A' of the carburetor with different branches of the manifold connection, thus insuring that the supply of explosive mixture for said cylinders will always be drawn from the carburetor. 80

I claim:

1. In a carburetor, the combination of a casing provided with a mixing chamber, a plurality of air admission passageways and a discharge opening, nozzles in said air admission passageways which communicate with a source of hydrocarbon supply, a valve which controls said air admission passageways, and means for varying the suction exerted on the exposed nozzles with the suction of the motor remaining uniform, said means comprising a separate valve which controls one of said air admission 95 passageways, substantially as described.

2. In a carburetor, the combination of a casing provided with a mixing chamber, a plurality of air admission passageways and a discharge opening, nozzles in said passageways which communicate with a source of hydrocarbon supply, a valve which controls said air admission passageways, means for varying the suction exerted on the exposed nozzles with the suction of the motor 105 remaining uniform, said means comprising a separate valve which controls one of said air admission passageways, a spring applied thereto for opening the same and manually operated means for closing said valve, substantially as described.

3. In a carburetor, the combination of a casing provided with a mixing chamber, a plurality of air admission passageways and a discharge opening, nozzles in said passageways which communicate with a source of hydrocarbon supply, a valve which controls said air admission passageways, a separate valve which controls one of said air admission passageways, a spring applied to 120 said valve for opening the same, and means for closing said valve controlled by movement of said throttle valve to close the same, substantially as described.

4. In a carburetor, the combination of a 130

casing provided with a mixing chamber, a plurality of air admission passageways and a discharge opening, nozzles in said passageways which communicate with a source 5 of hydrocarbon supply, a throttle valve which controls said air admission passageways, means for operating the same comprising, a throttle lever, a separate slide valve which controls one of said air admission 10 passageways, a pivoted lever connected to said slide valve, a spring applied to said lever adapted for opening said slide valve, and a cam surface formed on said lever which cooperates with the throttle lever to 15 close said slide valve when said throttle lever is turned to close the throttle valve, substantially as described.

5. In a carbureter, the combination of a casing provided with a mixing chamber, a 20 plurality of air admission passageways and a discharge opening, nozzles in said air admission passageways which communicate with a source of hydrocarbon supply, a throttle valve which controls said air admission 25 passageways, a separate slide valve which controls one of said passageways, a pivoted lever connected thereto, a spring applied to said lever for opening said slide valve and manually controlled means for 30 imparting pivotal movement to said lever for closing said slide valve, substantially as described.

6. In a carbureter, the combination of a casing provided with a mixing chamber, a 35 plurality of air admission passageways and a discharge opening, nozzles in said air admission passageways which communicate with a source of hydrocarbon supply, a throttle valve which controls said air admission 40 passageways, a separate slide valve which controls one of said passageways, a pivoted lever connected thereto, a spring applied to said lever for opening said slide valve and manually controlled means for 45 imparting pivotal movement to said lever for closing said slide valve, said means comprising a post pivoted to said lever, a wire which extends through a hole formed in said post, a button secured to said wire so as to 50 be adjustable lengthwise thereof, and means for imparting endwise movement to said wire, substantially as described.

7. In a carbureter, the combination of a casing provided with a mixing chamber, a 55 plurality of air admission passageways and a discharge opening, nozzles in said air admission passageways which communicate with a source of hydrocarbon supply, a pair of shutter valves which control said 60 air admission passageways, and means for imparting pivotal movement to said valves, toward and from each other, said valves being constructed and arranged to open and close said air admission passageways in succession, substantially as described.

8. In a carbureter, the combination of a casing provided with a mixing chamber, a plurality of air admission passageways and a discharge opening, nozzles in said air admission passageways which communicate 70 with a source of hydrocarbon supply, a pair of shutter valves which control said air admission passageways, and means for imparting pivotal movement to said valves toward and from each other, said valves being provided with openings of different operative lengths in line with different air admission passageways, the relation being such that as said valves open and close the air admission openings will be opened and 80 closed in succession, substantially as described.

9. In a carbureter, the combination of a casing provided with a mixing chamber, an air admission opening and a discharge opening, 85 a nozzle in said air admission opening which communicates with a source of hydrocarbon supply, a shaft rotatably mounted in the walls of the carbureter and which extends across the mixing chamber therein, 90 means for rotating said shaft, a pair of shutter valves mounted on said shaft and which control the air admission passageway, one of said valves being secured to rotate with said shaft and the other being loose thereon, 95 and gearing connecting said shaft with said loose valve, the relation being such that rotation of said shaft will impart movement to said shaft toward and from each other, substantially as described. 100

10. In a carbureter, the combination of a casing provided with a mixing chamber, an air admission opening and a discharge opening, 105 a nozzle in said air admission opening which communicates with a source of hydrocarbon supply, shafts rotatably mounted in the walls of the carbureter and which extend across the mixing chamber therein, means for rotating said shafts and a pair 110 of shutter valves which control the air admission passageway mounted on one of said shafts, one of said valves being secured to rotate with said shaft and the other being free to turn thereon, and gearing connecting said loose valve, with the other shaft, the 115 relation being such that rotation of said valve shaft will impart movement to said valves toward and from each other, substantially as described.

11. In a carbureter, the combination of a 120 casing provided with a mixing chamber, an air admission opening and a discharge opening, a nozzle in said air admission opening which communicates with a source of hydrocarbon supply, shafts rotatably mounted in 125 the walls of the carbureter and which extend across the mixing chamber therein, pairs of shutter valves mounted on said shafts, respectively, one pair of which controls the air admission passageway and the 130

- other the discharge opening, each of said pairs of valves comprising a valve secured to rotate with its shaft and a valve loose thereon and gearing connecting said shafts and loose valves whereby rotation of said shafts will impart pivotal movement to the valves of each pair of valves toward and from each other, substantially as described.
12. In a carbureter, the combination of a casing provided with a mixing chamber, an air admission opening and a discharge opening, a nozzle in said air admission opening which communicates with a source of hydrocarbon supply, shafts rotatably mounted in the walls of the carbureter and which extend across the mixing chamber therein, pairs of shutter valves mounted on said shafts, respectively, one pair of which controls the air admission passageway and the other the discharge opening, each of said pairs of valves comprising a valve secured to rotate with its shaft and a valve loose thereon and gearing connecting said shafts and loose valves whereby rotation of said shafts will impart pivotal movement to the valves of each pair of valves toward and from each other, said gearing comprising gears secured to rotate with said shafts, respectively, which intermesh with an intermediate idle gear, and gears secured to rotate with said shafts respectively, which intermesh directly with gears secured to rotate with the loose valve on the opposite shaft, substantially as described.
13. The combination with a main carbureter of an auxiliary carbureter comprising a passageway provided with an air admission opening and which communicates directly with the discharge opening from said main carbureter, a nozzle in said passageway which communicates with a source of hydrocarbon supply, a valve which controls said passageway, and means for operating said valve, said means comprising a spring applied to said valve for closing the same, and means for opening said valve controlled by movement of the throttle lever of the main carbureter to close the throttle valve thereof, substantially as described.
14. The combination with a main carbureter of an auxiliary carbureter comprising a passageway provided with an air admission opening and which communicates directly with the discharge opening from said main carbureter, a nozzle in said passageway which communicates with a source of hydrocarbon supply, a valve which controls said passageway, and means for operating said valve, said means comprising a spring applied to said valve for closing the same, and means for opening said valve comprising means controlled by movement of the throttle lever of the main carbureter to close the throttle valve thereof, and manually operated means, substantially as described.
15. The combination with a main carbureter of an auxiliary carbureter comprising a passageway provided with an air admission opening and which communicates with the discharge opening from said main carbureter, a nozzle in said passageway which communicates with a source of hydrocarbon supply, a valve which controls said passageway, and means for operating said valve, said means comprising a spring applied to said valve for closing the same, an arm which projects laterally from the stem of said valve, a cam on which said arm rides, a bell-crank lever pivoted on the carbureter casing, a link which connects one arm of said bell-crank lever with the arm on said valve stem and the other arm of which projects into the path of travel of a projection on the throttle valve lever of the main carbureter, the relation being such that movement of said throttle lever to close the throttle valve of the main carbureter will open the valve of said auxiliary carbureter, substantially as described.
16. The combination with a main carbureter of an auxiliary carbureter comprising a passageway provided with an air admission opening and which communicates with the discharge opening from said main carbureter, a nozzle in said passageway which communicates with a source of hydrocarbon supply, a valve which controls said passageway, and means for operating said valve, said means comprising a spring applied to said valve for closing the same, an arm which projects laterally from the stem of said valve, a cam on which said arm rides, a bell-crank lever pivoted on the carbureter casing, a link one end of which is adjustably connected to the arm on said valve stem and the other arm of said lever projecting into the path of travel of a projection on the throttle valve lever of the main carbureter, the relation being such that movement of said throttle lever to close the throttle valve of the main carbureter will open the valve of said auxiliary carbureter, substantially as described.
17. The combination with a main carbureter of an auxiliary carbureter comprising a passageway provided with an air admission opening and which communicates with the discharge opening from said main carbureter, a nozzle in said passageway which communicates with a source of hydrocarbon supply, a valve which controls said passageway, and means for operating said valve, said means comprising a spring applied to said valve for closing the same, an arm which projects laterally from the stem of said valve, a cam on which said arm rides, a bell-crank lever pivoted on the carbureter casing, an adjustable link which connects one arm of said bell-crank lever with the arm on said valve stem and the other arm

of which projects into the path of travel of a projection on the throttle valve lever of the main carburetor, the relation being such that movement of said throttle lever to close 5 the throttle valve of the main carburetor will open the valve of said auxiliary carburetor, substantially as described.

In testimony that I claim the foregoing

as my invention, I affix my signature in the presence of two subscribing witnesses this 10 22 day of May, 1915.

JOHN J. KARTHEISER.
